UNITED STATES PATENT OFFICE.

LOUIS COOPerman, OF NEW YORK, N. Y.

CROWN-ARTICULATOR.

1,345,433.

Specification of Letters Patent.

Patented July 6, 1920.

Application filed December 22, 1919. Serial No. 346,544.

To all whom it may concern:

Be it known that I, LOUIS COOPerman, a citizen of the United States, and a resident of the city, county, and State of New York, 5 have invented a new and useful Improvement in Crown-Articulators, of which the following is a specification.

The object of my invention is to provide a device of this character which may be 10 used in the conventional way, but which may be handled and manipulated with greater facility. This object is accomplished by my invention, one embodiment of which is hereinafter more particularly set forth.

15 For a more particular description of my invention, reference is to be had to the accompanying drawings, forming a part hereof, in which—

Figure 1 is a side elevation of my improved articulator with two castings in place.

Fig. 2 is a longitudinal section of my improved crown articulator.

Fig. 3 is a plan view of the same.

25 Fig. 4 is an enlarged sectional view, taken on the line 4—4 of Fig. 1.

Fig. 5 is a sectional view, taken on the line 5—5 of Fig. 2.

Fig. 6 is a modified form and jaw for 30 front teeth, the other figures showing jaws suitable for side teeth.

Throughout the various views of the drawings, similar reference characters designate similar parts.

35 My improved articulator 1 is provided with an upper jaw 2 and a lower jaw 3 which are connected by a pivot 4 from which extends a stem 5 and about which is placed a spring 6 (see Fig. 2), which has its ends 40 pressing against the interior of the respective jaws so as to hold them against the wings 7 of a washer 8 placed on the stem 5 and adjusted to any suitable position by means of a nut 9. For convenience, I prefer-

45 erably provide a second nut 10 in which is mounted a ring 11 so that, if desired, the crown articulator may be hung up to be gotten out of the way.

From the foregoing it is obvious that by 50 turning the nut 9 one way or the other on the stem 5, it is possible to shift the wings 7 in the direction of the axis of the stem 5 and thereby close the jaws 2 and 3 against the tension of the spring 6 or to permit this 55 spring to separate said jaws, according to the direction of movement of these wings.

When these wings move toward the pivot 4, the jaws are brought together and when these wings are taken away from the pivot 4, these jaws are separated. From this, it 60 is apparent that a micrometer adjustment may be had so that when the plaster casting of the teeth of a jaw is made in the conventional way and joined to the corresponding jaw in a manner which will be described 65 below, the teeth will be in their right occlusal relations. After they have been made in this way the nut 9 should remain in place and then one jaw may be separated from the other by sliding back the sleeve 70 12 on the jaw 2 to the position indicated in dotted lines in Fig. 2 when the extreme end of the jaw may be thrown up on a pivot 13 for the purposes of making the proper bridge or other work which is made in the 75 conventional manner.

The extreme ends of the jaws 2 and 3 are formed by means of curved plates 14 and 15, respectively, each of which has curved edges 16 and a center rib 17. Both 80 of these jaws have suitable shanks 18 which take into suitable recesses where they are held in place by capstan screws, 19, or similar devices. The upper plate 14 fits into a socket 20 which has an inner end adjoining 85 the pivot 13 on which it is mounted, and the other shank 18 extends into an opening 21 of the jaw 3 which is immediately over an enlarged base 22 which is preferably made integral with this jaw or substantially so 90 and wide enough to hold the articulator erect.

For the purposes of manipulation the sleeve 12 is preferably provided with a fin 23 which extends laterally therefrom, as 95 shown.

In view of the foregoing, the use of my improved crown articulator will be readily understood. Assuming the parts to be as indicated in Fig. 2 and it is desired to 100 prepare suitable dentistry, such as crown work, for the right side of a patient, a casting of the lower jaw 24 is put on the plate 15 in the conventional manner and thereafter the plate 14 is lowered by manipulating the screw 9 to the proper level, and then a second casting of plaster of Paris or similar material, 25, is secured to the plate 14 in the conventional manner, and when the castings 24 and 25 are together in their proper 110 occlusal relations, the sleeve 12 may be slid back, as indicated above, and then the plate

14 may be swung on the pivot 13 so as to facilitate a performance of the proper operations. Whenever desired this sleeve may be returned and if something is to be added to 5 the teeth between their occluding parts the nut 9 may be manipulated to correspond with a very nice micrometer adjustment, as indicated above. For side castings the plates 14 and 15, as shown in Figs. 1, 2 and 10 3, are sufficient. If front castings are required, the plate used in Fig. 6 may be employed. In any event the manipulations are the same, as above set forth.

15 While I have shown and described one embodiment of my invention, it is obvious that it is not restricted thereto, but is broad enough to cover all structures that come within the scope of the annexed claims.

20 Having thus described my invention, what I claim is:

1. A crown articulator provided with two jaws pivoted together by a pivot, a coil spring about said pivot with ends extending into said jaws and adapted to separate them, 25 a stem extending from said jaws, a washer mounted on said stem adapted to rest against said jaws in opposition to the ten-

sion of the spring, a nut mounted on said stem for determining the position of the washer and means connected to said jaws 30 for receiving castings.

2. A crown articulator, a pair of jaws pivoted together, a spring tending to separate said jaws, means for overcoming the tension of the spring and holding the jaws in fixed relation, plates adapted to receive castings and secured to said jaws and means for permitting one of said plates to be swung about a pivot in its jaw so that operations may be performed on the castings 40 without disturbing the initial set of the apparatus.

3. A crown articulator provided with a pair of jaws pivoted together, a spring normally separating said jaws, means for overcoming the tension of the spring and holding the jaws in fixed relation, a slideable sleeve mounted on one of said jaws, a pivot concealed by said sleeve so that the extreme end of one jaw may be thrown about the 45 pivot concealed by the sleeve and means for receiving castings at the ends of said jaws.

LOUIS COOPERMANN.
